Frank Kent
ATTORNEY.

UNITED STATES PATENT OFFICE.

RICHARD HOILE, OF VERONA, NEW JERSEY.

VANITY CASE.

Application filed June 1, 1923. Serial No. 642,779.

To all whom it may concern:

Be it known that I, RICHARD HOILE, a citizen of the United States, residing at Verona, in the county of Essex and State 5 of New Jersey, have invented certain new and useful Improvements in Vanity Cases, of which the following is a specification.

This invention relates to containers, and more particularly aims to provide a container of the so-called vanity case type, in which there may be housed not only a mirror, and preferably merely one such mirror, but both face-powder and rouge compacts, and preferably also a powder-15 puff for each compact or cosmetic cake; the entire construction being such that a simplified, most convenient and otherwise improved device is provided when the vanity case is open, and a small and attractively 20 proportioned trinket is provided when the case is closed.

In that the invention is preferably carried out by providing preferably a pair of cup-like permanently hingedly connected 25 casing members, in combination with a pivotally mounted intermediate structure for carrying dissimilar compacts on opposite sides of said intermediate structure, the new vanity case does not depart materially from 30 what has been heretofore proposed. A special object of the present invention, however, is to provide such intermediate structure so that the same includes in the main two parts, one a permanently incorporated 35 hingedly mounted member arranged intermediate the complementary casing members, and the other a reversible and hence revolvably mounted compact-support proper, pivotally mounted on the intermediate member, 40 a point or rather along a line removed from the line or lines of inter-pivoting of the intermediate member and the two casing members.

A further object of the invention is to 45 provide said permanently incorporated intermediate member of a particular design and for a particular purpose; and in that connection to provide the revoluble support of a particular construction; all 50 whereby said intermediate member, which is preferably of yoke-like design, is adapted readily detachably to carry the revoluble support and its compact. And having in mind the end last indicated, the invention 55 aims to provide the parts just mentioned

in combination with special journalling instrumentalities for the revoluble support and partially carried by support and yoke, and to provide said instrumentalities, preferably in part consisting of a yoke-like 60 intermediate member of inherently resilient material, such that the support is always instantaneously removable relative to its revoluble mount, and so that similar supports may be later purchased independently 65 as replacement units to be instantaneously substituted for a previously incorporated support, the compacts on opposite sides of which have been consumed.

A further object is to provide a vanity 70 case having a readily replaceable compact-support as above indicated, and having also means for revolvably mounting such support, but a case of exceedingly small size and yet adapted to provide, when closed, a special 75 compartment or holder for each of two different powder-puffs or dab-rags, one such puff or rag for each compact, and with one compartment or holder forming a permanent but inexpensive part of the replacement 80 unit aforesaid, that is, the compact support.

According to the construction hereinafter 85 described in detail, and constituting a preferred but merely illustrative embodiment of the invention—since the invention may be carried out, obviously, in a multiplicity of different ways and yet keep within the scope of protection indicated by the appended claims—an exceedingly inexpensive 90 replacement unit may be furnished, and one carrying, if desired, a pocket-establishing structure to receive say a small rouge-puff, offset from one side of the support and that side of the support carrying the rouge 95 compact. With such a support, the vanity case, when closed, may be quite thin and yet ideally provide a main powder-puff compartment offset from the side of the support carrying the face-powder compact; 100 and then, with the vanity case carrying interiorly but a single mirror, which is an important cost-reducing feature, such mirror may be located to be always removed from either compact and also from the face-powder puff and hence always to be unobscured by powder deposits. On the other hand, said single mirror is the only one required, due to the revoluble mounting of 105 the support on the intermediate member and 110

the hinge mounting of such intermediate member relative to the complementary casing members, one of which latter carries said mirror; all as will be clear from the following description of said preferred embodiment as shown in the accompanying drawing.

In said drawing, Figure 1 is a perspective view, showing the case closed;

10 Figure 2 is a view similar to Figure 1, showing the case partially open, that is, with the upper casing member swung away from the other parts to disclose the single mirror furnished;

15 Figure 3 is a transverse sectional view, showing both casing members swung away from the intermediate yoke-like member and its revolvably carried support or platform for the two compacts; and

20 Figure 4 shows the parts as in Figure 3, but with the compact support in a different position and with the rouge powder-puff removed from its holder forming a permanent part of the replaceable support.

25 Referring more particularly to the details of construction shown in the drawing, the complementary casing members are indicated at 5 and 6. These are substantially similar, in that each is a cup-like structure 30 having a continuous skirt as shown.

Only the upper of these two complementary casing members is provided with a mirror, such mirror being shown at 7, and being suitably permanently anchored in 35 place.

These two members 5 and 6 are pivotally interconnected, or hinged together, as indicated at 8. As will be seen, when Figure 1 is compared say with Figure 3, the hinge 40 means 8 includes three leaves, two of which are respectively secured to the two casing members 5 and 6, and the third of which, marked 8^a, is swingable relative to either of the other two leaves and hence relative 45 to either of the casing members.

It is this third leaf 8^a which hingedly mounts an intermediate member 9, here of semi-circular yoke-like construction; the swinging end of leaf 8^a being suitably secured to the intermediate member, herein-after called the yoke, midway of the free 50 ends of the latter.

The revolvble support is a disc-like member or platform 10 having suitably permanently adherent to opposite faces thereof two compacts, one marked 11 and being a cake of face-powder, and the other marked 12 and being a smaller case of rouge.

Support 10 is revolvably mounted on yoke 60 9 by means of pivot-pins 13 on the outer ends of the latter, facing each other, and aligned substantially parallel to the axis of hinge 8. These pins are seated in recesses or sockets cut in the cylindrical wall of support 10 at diametrically opposite points.

The support may be of wood or any other suitable material, but the yoke, at least in the case of the present embodiment, is of spring metal having such a resilient set that with the parts arranged as shown in the drawing, the support may be readily revolved when the case is open as shown in Figures 3 and 4, and yet the yoke arms may be readily pried apart or pulled away from each other by the fingers, for the removal of a support 10 and the substitution of another support with new compacts. Thus the revolvble mounting of each support 10 is one including a plurality of aligned journaling devices, each such device including a pin and a socket, and a revolvble mounting such that a new compact carrying unit or support 10 may be readily substituted for another, yet such a mounting that a revolvble incorporated compact-support may never be accidentally displaced from its yoke.

As shown in Figure 3, the support may be arranged parallel with and between the upper and lower planes of the preferably band-like yoke; and then the casing members 5 and 6 may be snapped closed to house all the parts protectively against each other. Such parts include a face-powder-puff 14 normally accommodated in its own compartment within the interior of casing member 6; a pocket establishing structure 14^a permanently carried by support 10 over rouge compact 12; and a rouge-puff 15, dab-rag or the like. It is desirable of course that the support 10 be arranged as shown in Figure 3, that is with the compact 11 lowermost and facing powder-puff 14, when the case is closed. In use, however, it will be understood that once the parts are arranged as shown in Figure 3, that is, the two casing members and the intermediate structure arranged divergently, the support 10 is revolved through 180 degrees or maintained as shown in Figure 3, according as it is desired to use the compact 12 or the compact 11. In using the latter compact, the rouge-puff 15 is of course employed. In using the compact 12, the powder-puff 14 is of course employed. In either case, the single mirror serves.

As hereinbefore indicated, variations may be freely resorted to, within the scope of the following claims.

I claim:—

1. A vanity case including three hingedly connected members, two of such members being cup-like top and bottom case-subdivisions, and the third being intermediate the members last-mentioned but movable relative to either thereof, said intermediate member carrying a revolvble plate-like support.

2. A vanity case including three hingedly connected members, two of such members being cup-like top and bottom case-subdivi- 125

sions, and the third being intermediate the members last-mentioned but movable relative to either thereof, said intermediate member carrying a revolute plate-like support 5 carrying on opposite faces compacts of dissimilar nature.

3. A vanity case including three hingedly connected members, two of such members being cup-like top and bottom case-subdivisions, and the third being intermediate the members last-mentioned but movable relative to either thereof, said intermediate member carrying a revolute plate-like support carrying on opposite faces compacts of dissimilar nature, one of which is a face-powder compact, there being also provided a mirror in one of said case-subdivisions, a compartment being provided for a powder-puff for the last-mentioned compact in the other case- 15 subdivision when the case is closed.

4. A vanity case including three hingedly connected members, two of such members being cup-like top and bottom case-subdivisions, and the third being intermediate the members last-mentioned but movable relative to either thereof, said intermediate member carrying a revolute plate-like support having permanently affixed to one side thereof a face-powder compact and permanently 25 affixed to the other side thereof a rouge compact, said support and its compacts forming a reversible cosmetic tray and one of said case-subdivisions carrying an interior mirror observable whichever compact is offered by 35 such tray.

5. A vanity case including three hingedly connected members, two of such members being cup-like top and bottom case-subdivisions, and the third being intermediate the members last-mentioned but movable relative to either thereof, said intermediate member carrying a revolute plate-like support having permanently affixed to one side thereof a face-powder compact and permanently 40 affixed to the other side thereof a rouge compact, said support and its compacts forming a replaceable unit relative to the intermediate member, to this end there being provided readily releasable means revolutely mounting the support on the intermediate member.

6. A vanity case including three hingedly connected members, two of such members being cup-like top and bottom case-subdivisions, and the third being intermediate the members last-mentioned but movable relative to either thereof, said intermediate member carrying a revolute plate-like support having permanently affixed to one side thereof a face-powder compact and permanently 45 affixed to the other side thereof a rouge compact, said support and its compacts forming a reversible cosmetic tray and one of said case-subdivisions carrying an interior mirror observable whichever compact is offered by 50 such tray, said support also carrying a

pocket-establishing structure for releasably holding a powder-puff.

7. A vanity case including three hingedly connected members, two of such members being cup-like top and bottom case-subdivisions, and the third being intermediate the members last-mentioned but movable relative to either thereof, said intermediate member carrying a revolute plate-like support carrying on opposite faces compacts of dissimilar nature, one of which is a face-powder compact, there being also provided a mirror in one of said case-subdivisions, a compartment being provided for a powder-puff for the last-mentioned compact in the other case-subdivision when the case is closed, and there being further provided a pocket-establishing structure on the support so disposed and arranged relative to the other compact that a powder-puff for said other compact may be removably wedged in such pocket to overlie said other compact. 70 75 80 85

8. A vanity case including three hingedly connected members, two of such members being cup-like top and bottom case-subdivisions, and the third being intermediate the members last-mentioned but movable relative to either thereof, said intermediate member carrying a revolute plate-like support, said intermediate member being a frame carrying at diametrically opposite points journaling means for the support, said journaling means including co-acting pin and socket elements carried by the intermediate member and by the support and one of such elements being resiliently biased to a certain position relative to another whereby the support is normally securely mounted for revolution yet may be readily 90 95 100 105 bodily separated from the intermediate member.

9. A vanity case including three hingedly connected members, two of such members being cup-like top and bottom case-subdivisions, and the third being intermediate the members last-mentioned but movable relative to either thereof, said intermediate member carrying a revolute plate-like support, said intermediate member being a yoke carrying resiliently at its free ends shaped elements constituting parts of pairs of aligned pin and socket means for revolutely mounting said support as aforesaid, said means being partially carried by said support. 110 115 120

10. A vanity case including concave top and bottom members permanently hingedly connected and having matching skirt portions, a mirror in one of said members, a frame-like intermediate member permanently hingedly connected to one of the first-mentioned members, and a revolute support adapted permanently to carry dissimilar compacts on opposite sides thereof, 125 130

said support being impermanently pivotally mounted on the intermediate member, and said three members and the support being so constructed and arranged that when 5 the case is closed the intermediate member and the support are housed completely within the two first-mentioned members and when the case is open the support is freely revoluble relative to the intermediate members.

11. A vanity case including concave top and bottom members permanently hingedly connected and having matching skirt portions, a mirror in one of said members, a 15 frame-like intermediate member permanently hingedly connected to one of the first-mentioned members, and a revoluble support adapted permanently to carry dissimilar compacts on opposite sides thereof, said support being impermanently pivotally mount- 20

ed on the intermediate member and said three members and the support being so constructed and arranged that when the case is closed the intermediate member and the support are housed completely within the two first-mentioned members and when the case is open the support is freely revoluble relative to the intermediate members, said support carrying a pocket-establishing structure adapted releasably to hold a powder-puff, and the parts being further so constructed and arranged that with the case closed a powder-puff received as just described may be housed within the case directly opposite said mirror thereby to establish a compartment on the opposite side of the support for accommodating a second powder-puff.

In testimony whereof I affix my signature.
RICHARD HOILE.
